UNITED STATES PATENT OFFICE

2,313,370

RADIATING FURNACE

Claude L. Spring, Des Moines, Iowa

Application December 18, 1940, Serial No. 370,584

1 Claim. (Cl. 126—99)

The principal object of my invention is to provide a radiating furnace that will efficiently radiate a great amount of heat and which has reduced radiating flues to present a radiating surface consistent with the reduction of volume in the cooling gases passing therethrough.

A further object of this invention is to provide a radiating furnace structure having a long heat travel contained in a small space and one which has a great amount of radiating surface.

A still further object of my invention is to provide a radiating furnace structure that is extremely economical in manufacture, durable and efficient in use.

These and other objects will be apparent to those skilled in the art.

My invention consists in the construction, arrangement and combination of the various parts of the device, whereby the objects contemplated are attained as hereinafter more fully set forth, pointed out in my claim and illustrated in the accompanying drawings, in which:

Fig. 1 is a side cross sectional view of my complete furnace construction taken on the line 1—1 of Fig. 2.

Fig. 2 is a front elevational view of the furnace and radiator more fully illustrating its construction.

Fig. 3 is an end cross sectional view of a portion of the furnace taken on the line 3—3 of Fig. 1.

Fig. 4 is a top cross sectional view of the furnace taken on the line 4—4 of Fig. 1.

There are a great number of furnaces on the market designed for specific types of heating units. Some of these furnaces are bulky, do not have sufficient radiating surfaces within the furnace jacket and do thereby permit high stack temperatures and lower the efficiency of the furnace as a heating medium. Furthermore, these furnaces have a radiating stack of the same dimension throughout, whereas the gases are condensed as they cool, thereby preventing the utilization of a great amount of heat with attendant high stack loss. I have overcome such disadvantages as will be appreciated, and as will be hereinafter more fully set forth.

Referring to the drawings, I have used the numeral 10 to designate the combustion chamber of my furnace having a fuel inlet 11 through which may be introduced any type of heating element such as the nozzle of an oil burner, which I have designated by the numeral 12. The numeral 13 indicates legs formed on the bottom portion of the chamber 10. The numeral 14

5 indicates a horizontally disposed radiating chamber in communication with the upper end of the combustion chamber 10 and extending rearwardly therefrom. The numeral 14' indicates a visual inspection window placed in the forward end of the tube 14 as shown in the drawings. The numeral 15 indicates a housing having its lower end open and in communication with the upper rearward end of the radiating chamber 14. I have used the numerals 16 and 17 to indicate 10 two flues each having their rearward end in communication with the upper end of the housing 15 extending forwardly and tapering to a smaller area toward their forward ends. The numeral 18 indicates a second housing of smaller capacity than the housings 15 and having its lower inside portion in communication with the smaller ends of the tubes 16 and 17. The numeral 19 indicates a tube having its forward end 15 in communication with the inside of the housing 18, tapering to a smaller area as it progresses away from the housing 18 and terminating in a stack flange 20 as shown in Fig. 1 of the drawings. I have used the numeral 21 to indicate a 20 jacket placed about the furnace unit in the usual manner and having the ordinary outlet pipe 22 and inlet pipe 23 as shown by dotted lines in Fig. 1 of the drawings.

The practical operation of my device is as follows:

Heat is generated within the combustion chamber 10 through the medium of an oil burner, stoker, or other source of suitable heat supply, and the hot gases rise and are drawn by chimney draft upwardly and into the radiating chamber 14. This radiating chamber has a smaller diameter or area than the area of the combustion chamber 10 to compensate for the contraction of the gases as they are cooled. The gases 35 then pass into the housing 15, thence into the larger ends of the tubes 16 and 17 and thence pass into the housing 18, through the tube 19 and into the chimney or stack. The areas of the various units of the furnace are progressively 40 smaller. The housing 15 is of smaller capacity than the chamber 14, the tubes 16 taper from the chamber 15 to the chamber 18, the chamber 18 is of smaller capacity than the entire outlet area of the tubes 16 and 17, and the stack portion 20 45 is of smaller area than the inlet of the tube 19 at its junction with the housing 18. The entire outer surface area of the chamber 10, the radiating chamber 14, the housings 15 and 18, the tubes 16 and 17, and the tube 19 are radiating surfaces radiating heat into the jacket or casin-

21. The progressive tapering of the radiating flues provide for the close adherence of the contracting gases to the radiating surfaces, thereby preventing loss of heat through gas expansion and preventing a stack draft in excess of the amount required for the heat generated. Although I have shown the tubes 16, 17 and 18 as being round, they may be of any shape, so long as they are reduced progressively in proportion to the cooling of the gases and consequent condensing of the gases as they lose their heat to the radiating surfaces. The visual inspection window 14' may be used for viewing the flame within the combustion chamber.

Thus it will be seen that I have provided a radiating furnace structure which fulfills all of my objects, is efficient, provides for the economical combustion of the fuel, provides adequate radiating surface, a low stack temperature and high efficiency relative to the heat generated. My furnace structure makes possible a great economy in fuel and prevents losses of heat energy.

Some changes may be made in the construction and arrangement of my improved radiating furnace without departing from the real spirit

and purpose of my invention, and it is my intention to cover by my claim any modified forms of structure or use of mechanical equivalents which may be reasonably included within their scope.

6 I claim:

In a radiating furnace structure, a combustion chamber, a housing in communication with the upper end of said combustion chamber and having a smaller volume than said combustion chamber, a second housing having a smaller volume than said first mentioned housing, a plurality of tapered flue elements each having their larger ends in communication with said first mentioned housing and their smaller ends in communication with said second mentioned housing, and a tapered flue member having one of its ends in communication with said second mentioned housing being progressively reduced in area as it progresses away from said second mentioned housing and terminating in a stack flange; said first and said second mentioned housings together with said flue members presenting a continuous progressive reduction of capacity from said combustion chamber to said stack flange.

15 20 CLAUDE L. SPRING.
